UNITED STATES PATENT OFFICE.

REINOLD BERRENBURG, OF BOSTON, MASSACHUSETTS.

APPARATUS FOR PRODUCING HIGH PRESSURES.

1,346,165.

Specification of Letters Patent. Patented July 13, 1920.

Application filed February 10, 1917. Serial No. 147,915.

To all whom it may concern:

Be it known that I, REINOLD BERRENBURG, a citizen of the United States, residing at Boston, in the county of Suffolk and State 5 of Massachusetts, have invented a new and useful Improvement in Apparatus for Producing High Pressures, of which the following is a specification.

The present invention relates to apparatus 10 for producing high pressures, and more particularly to such apparatus for use in motor cars to pump the tires thereof full of air.

The object of the present invention is to 15 produce an apparatus of the type hereinbefore referred to which will produce high pressures in an economic manner and which will pump air into pneumatic tires without liability of oil or other lubricant used in the 20 apparatus entering with the air into the tires.

To the accomplishment of this object and such others as may hereinafter appear, the 25 various features of the present invention consist in certain devices, combinations and arrangements of parts fully set forth hereinafter, the advantages of which will be readily understood by those skilled in the art.

The various features of the present invention will be readily understood from an 30 inspection of the accompanying drawings, in which,

Figure 1 is a detail in side elevation, 35 partly in section, of the apparatus;

Fig. 2 is a detail in front elevation, partly in central, vertical section, of the apparatus; and

Fig. 3 is a sectional detail of the adjusting means for the blade actuating ring.

In the illustrated embodiment of the invention an air-tight tank is mounted on a suitable base 2. Mounted on one end wall of the tank 1 is a casing 3 for a rotary pump. 45 This pump comprises a carrier 4 provided with a series of blades or pistons 5 loosely mounted in slots 6 formed in the carrier 4. The carrier 4 is arranged to fit the upper part of the casing 3 and leave a chamber 7 between the carrier and casing in the lower part of the casing.

The carrier 4 is rotated by a horizontal shaft 8 which extends through a stuffing box 9 on the tank 1 and which is driven from 55 some suitable source of power. During the rotation of the carrier, the blades 5 are

pushed outwardly in the slots 6 to contact with the casing 3 by a ring 10 which surrounds the shaft 8 and a roll 11 loosely mounted on a stud 12 secured to the casing. 60 The casing 3 is provided with a slot 13 to permit the adjustment of the roll 11 and thus change the position of the ring 10.

The casing 3 is provided with an inlet port 14 and an outlet port 15. The port 14 65 communicates with the chamber 7 into which the air to be compressed is supplied by a horizontal pipe 16 provided with a check valve 17. The inlet port 14 is located a substantial distance below the horizontal 70 plane passing through the axis of the shaft 8, whereas the upper edge of the outlet port 15 is substantially coincident with said plane. With this construction the air is drawn through the port 14 at a time when 75 the space inclosed between the blades 5 nearest the port 14 is increasing in size. When the bucket formed by the blades between which the air is trapped passes the lowest point in the casing the space with- 80 in the bucket decreases in size thus causing the air in the bucket to be compressed. The compressed air is discharged through the outlet port 15 into a vertical riser 18 which conducts the air to the tank 1.

In order to seal the internal parts of the pump and thus prevent leakage of air either through the casing or from one bucket to another the tank 1 is provided with a lubricant, such as glycerin, or oil, to a depth indicated by the line 19 which is below the upper 85 end of the riser 18. This lubricant is subjected to the pressure of the air discharged into the tank 1 and is forced through a screen 20 and a needle hole 21 into the inlet 90 port or casing 3. This lubricant entering the casing effectively seals the space between the blades and the casing and thus prevents the leakage of air from one bucket to another. Moreover the air pressure acting on 100 the lubricant forces the flat end walls of the casing against the edge faces of the rotating blades, thereby tightening the joints between the blades and the end walls.

The roof of the tank or reservoir 1 is 105 concaved and the riser 18 is arranged to discharge the air and accumulations of lubricant directly against the concaved roof. This construction causes the lubricant to strike the arched roof with such force as to 110 separate it from the air which is deflected in its course by the curved roof. The air is

thus caused to circulate across an outlet 22 in the roof until the air is again deflected by the wall 23 into the air-storage part of the tank. The stored air is drawn as needed 5 through the outlet 22 free from traces of the lubricant thus making the present invention particularly useful in filling pneumatic tires.

When the pump is not in use the lubricant gradually fills the inlet port 14 and the pipe 10 16 back to the check valve 17. When the pump is rotated this accumulation of lubricant is discharged from the riser 18 and spattered against the arched roof. The lubricant is thus separated from the air and 15 returned to the body of lubricant in the reservoir.

What is claimed as new, is:

1. An apparatus for producing high pressures, having, in combination, a tank for 20 storing lubricant and compressed air, said tank having an arched roof and an outlet formed therein, an air compressor immersed in the lubricant in said tank, a discharge pipe for the compressed air and accumulations of lubricant opening into the tank above the level of the lubricant therein and adapted to discharge directly against the arched roof at one side of the outlet therein, whereby the lubricant is separated from the 25 air, substantially as described.

2. An apparatus for producing high pressures, having, in combination, a rotor provided with a series of radially disposed slide- 30 able blades providing buckets between said blades, a casing in which said rotor is

mounted having a chamber that is traversed by said blades, said casing being provided with inlet and outlet ports at the opposite ends of said chamber and having a restricted aperture formed therethrough to 40 lead lubricant directly to the surface of said chamber traversed by the outer ends of said blades while the buckets are in communication with said inlet port, and means coöperating with said casing to supply lubricant 45 to said restricted aperture and to conduct the lubricant externally of said casing from said outlet port to said aperture.

3. An apparatus for producing high pressures, having, in combination, a rotor provided with a series of radially disposed slide- 50 able blades providing buckets between said blades, a casing in which said rotor and said blades are rotatably mounted, said casing being provided with inlet and outlet ports, and having a chamber connecting said ports, which chamber is traversed by said buckets, a lubricant tank into which the outlet from said casing discharges at a point above the 55 level of the lubricant in said tank, said casing being immersed in the lubricant in said tank and having a restricted inlet admitting lubricant into each bucket when the same is in communication with said inlet port, whereby the body of the lubricant in said 60 tank will be subjected to the pressure produced in said apparatus, and the lubricant will be forced through said restricted opening by said pressure.

REINOLD BERRENBERG.
